Primary Examiner — Michael C Stout*Assistant Examiner* — Fitzgerald L Butac(57) **CLAIM**

The ornamental design for a liquid delivery system lid, as shown and described.

DESCRIPTION

FIG. 1 is a perspective view of a liquid delivery system lid embodying the new design.

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof; and,

FIG. 8 is a perspective view thereof along with other components of a liquid delivery system.

The broken, dashed lines in the drawings are shown for illustrative purposes only and form no part of the claimed design.
